UNITED STATES PATENT OFFICE.

HAROLD SAGE TRUSCOTT, OF MAKAWELI, TERRITORY OF HAWAII.

ENTRAINMENT-TESTER.

1,142,287.

Specification of Letters Patent. Patented June 8, 1915.

Application filed August 14, 1913. Serial No. 784,759.

To all whom it may concern:

Be it known that I, HAROLD SAGE TRUSCOTT, a subject of the King of Great Britain, residing at Makaweli, county of Kauai, Territory of Hawaii, have invented certain new and useful Improvements in Entrainment-Testers; and I do hereby declare the following to be a full, clear, and exact description of the invention, such as will enable others skilled in the art to which it appertains to make and use the same.

This invention relates to means for determining the losses by entrainment in evaporating apparatus.

15 It is particularly adapted for use in connection with the vapor pipes between vacuum pans or evaporating effects and their condensers such as are commonly used in sugar house work.

20 The sugars or other materials which are lost by being carried over in the vapor from the cell to the condenser and then discharged with the waste water are termed entrainment losses. The present method of ascertaining these losses is by sampling the waste water from the condenser and determining the losses by chemical analysis of these samples, the results being more or less inaccurate and unreliable. Entrainment is seldom 25 continuous, but is usually intermittent or at least is greater at some periods than at other periods during the evaporating process.

The object of the present invention is to 30 provide means within the easy control of the operator for obtaining continuously representative samples of the vapor in a condensed form and taken while the vapor is passing through the vapor pipe and before it reaches the condenser, thus eliminating 35 from these samples the cooling water used in the condenser. From the analysis of such samples the amount of these losses may be accurately determined, and by taking the samples at regular intervals the periods during 40 which entrainment occurs may be definitely ascertained. The operator is therefore thus kept informed, so that by regulating the evaporation the entrainment losses may be prevented or at least greatly reduced 45 and a saving of sugar or other material thereby be effected which has heretofore been lost.

The invention contemplates a device introduced in the vapor pipe adjacent to the 50 condenser, comprising a vapor receiving chamber open to receive the vapors moving

toward the condenser which meet the chamber in their path, means to condense the vapors entering said chamber, and means for withdrawing samples of the condensed vapor from said chamber. To find the correct amount of entrainment loss, if a is the area of the opening in the vapor receiving chamber, A the area of the vapor pipe, and x the sugar or other material found by an analysis of the sample, then the total entrainment loss X during the period the sample was being condensed will be found by direct proportion:

$$a : A :: x : X, \text{ or } X \text{ equals } \frac{Ax}{a}. \quad 70$$

One embodiment of my invention is disclosed in the structure illustrated in the accompanying drawings, forming a part of this specification, in which—

Figure 1 is a sectional elevation of an entrainment tester constructed in accordance with the present invention; Fig. 2 is a section on the line A—B of Fig. 1; and Fig. 3 shows on a smaller scale the device applied to the vapor pipe between the cell of a vacuum pan or of an evaporator and its condenser.

Referring to the drawings, the cylindrical casing or body 1 of the device is tightly fitted in any well known manner through a hole in the top and the bottom respectively of the vapor pipe, preferably near the condenser, so that said casing or body 1 projects both above and below the vapor pipe. The vapor receiving chamber 2 is eccentrically located within the body 1, and an opening 3 is made in both the body 1 and the chamber 2 along that portion of their tangential line of contact which is within the vapor pipe. The joints around the opening 3 between the body 1 and the chamber 2 are soldered or brazed so as to be air or water tight. Vapors moving in the vapor pipe toward the condenser, as shown by arrows in Fig. 1, thus enter the chamber 2 through the opening 3. A circulation of cooling water to condense the vapors in the chamber 2 may be maintained through the body 1, the water entering through the nozzle 4 near the bottom and leaving through the nozzle 5 at the top, as shown. The cock 6, Y connection 7, and valves 8 and 9 are provided at the lower end of the device, as shown. 110

It will now be noted, that the chamber 2 is kept cooled by the surrounding water

passing through the body 1, that the vapors entering the chamber 2 through the opening 3 will be condensed within said chamber, and that samples of the vapor thus condensed may be withdrawn from the chamber 2 into one of the receptacles 10 by operating the cock 6 and one of the valves 8 or 9. The device does not obstruct the flow of vapor in the vapor pipe, but assists the condenser, because the vapor in contact with the outside of the body 1 is condensed and the vapors entering the opening 3 are condensed within the chamber 2.

I claim:

1. The combination with evaporating apparatus and a vapor pipe leading therefrom, of an entrainment tester comprising, a vapor receiving chamber adapted to be

located within said vapor pipe, means for cooling said chamber, and means for withdrawing samples of the vapor condensed within said chamber, substantially as described. 20

2. The combination with a vapor pipe, of a vapor receiving chamber adapted to collect a portion of the vapor passing through said pipe, means to cool the vapor so collected to condense the same, and means for withdrawing portions of the condensed vapor, substantially as described. 25 30

In testimony whereof I affix my signature, in presence of two witnesses.

HAROLD SAGE TRUSCOTT.
